UNITED STATES PATENT OFFICE.

FRANK E. WOODFORD, OF CHICAGO, ILLINOIS.

CAR-HANDLING APPARATUS.

1,225,694.

Specification of Letters Patent.

Patented May 8, 1917.

Application filed December 20, 1911. Serial No. 667,047.

To all whom it may concern:

Be it known that I, FRANK EDWARD WOODFORD, a citizen of the United States, and a resident of Chicago, in the State of Illinois, have invented certain new and useful Improvements in Car-Handling Apparatus, of which the following is a specification:

My present invention relates in general to apparatus for automatically transferring materials, and more particularly to an improved system of tracks and electric circuits peculiarly adapted to such apparatus, though of general utility, and has special reference to the provision of improved automatic motor and brake actuating circuits and devices for controlling cars as well on shuttle as on continuous tracks, adapted to handle such cars from one or more central stations at a greater or less distance from such cars.

The principal objects of my present invention are the provision of improved means for controlling the movements of the cars from a common switchboard; to provide improved automatic apparatus driving the cars, for accelerating, retarding and generally controlling the speed and movement thereof, and for applying the brakes not alone to vary the speed thereof but to entirely stop and hold the car; to apply such control to one or more cars independently of other cars running on the same rails or driven from the same source of current supply; the provision of means for supplying in alternation through a common conductor a plurality of currents at varying potentials for actuating different devices; the provision of electrically operated means for driving a car motor and applying the brake of a car in alternation so that the motor is not supplied with current while the brakes are being applied and vice versa, including a common conductor; the provision of an improved controller device for operating electrical circuits of relatively high potentials; the provision of improved means for protecting such circuits in general and more especially on switchboards and at points distant from the switchboard; the provision of improved means for protecting circuits, and especially nominally closed circuits, adapted for carrying currents of varying potentials;

the provision of improved brake-mechanism and of circuits for operating the same, together with certain additional objects to be 55 hereinafter disclosed.

Apparatus for the above mentioned purposes and attaining the above stated objects, are useful for many purposes but have been especially provided by me and applied to a 60 system of independent cars on a shuttle track for carrying commodities from a place of loading to a place of discharge, for example, for carrying clay from a shovel to a brick machine in a brick manufacturing 65 establishment.

In accomplishing the stated objects, I have provided certain arrangements and structures, illustrated in a preferred form in the accompanying drawings wherein— 70

Figure 1 is a general wiring diagram of the tracks, switchboards, conductors for both the driving and the braking circuits, and the current feed supplies therefor;

Fig. 2 is a diagrammatic view of the car 75 wiring and circuit changer, including both the motor and the brake circuits and also the circuit changer circuit, the several connections to and between such circuits, and the circuit protecting means;

Figs. 3 and 4 are respectively side and end elevational views of a preferred form of controller device for use on the switchboard;

Fig. 5 is a fragmentary elevational view of part of the structure of Figs. 3 and 4 85 taken on line V of Fig. 3; and

Figs. 6 and 7 are respectively plan and elevational views, both partly in section, of a preferred form of brake-device for the car, and means for actuating the same. 90

Fig. 8 is a diagram illustrative of the switchboards, conductors and current feed supplies reduced to their simplest form.

Before describing the drawings in detail, it is to be observed that the system shown 95 therein is but one embodiment of my invention for the sake of illustration, and it is to be premised that the several cars used therein are each equipped with a driving motor, an electrically operated brake and a 100 collector, such as a trolley or rail shoe.

According to my invention, means are provided for lowering the voltage supplied to the cars on the tracks whenever it is de-

sired to apply the car brakes, and for raising the voltage to its normal value to release the brakes and start the car motors again. The means adopted for controlling the voltage applied to the cars is shown diagrammatically in its simplest form in Fig. 8 of the accompanying drawings which will be explained before the more detailed arrangement of Fig. 1 is described.

10 Current is supplied from the generator M one terminal of which is grounded to the track 10 by lead w^6 , while its other terminal is connected by means of the lead w^5 to switch contacts 19^a and 22. In the ordinary 15 operation of the car the switch point 19^a is connected to switch point 19 by means of a switch, while the switch between points 22^a and 22^b is open. Current then flows along w^5 to the contact a^2 of a double rheostat S. The contact a^2 is connected to the contact a' by means of the resistance R_{x2} , and, in turn, contact a' is connected to the contact a by means of the resistance R_v . Opposite these contact points is arranged a segmental contact ax adapted to be connected with any one of the contacts a , a' or a^2 by moving the arm of the rheostat to the right. With the rheostat arm in contact with the contact a^2 , the resistances R_v and R_{x2} are short-circuited and the current from the generator 30 M flows without resistance to the contact a of the magnetic blow out device X, and from thence by contact plate x^2 to the contact x' , leads 16^b, 16^a and switch contact 17^a.

35 A switch is provided for connecting the contact 17 with either contact 17^a or 17^b as desired. The current then flows through lead 16 to the conductor 15 adjacent the track. It will be seen that a second rheostat is provided over the one just described which is connected in parallel with the first rheostat so that it can be used in place of the latter by merely throwing the switch from the point 17 over to the contact 17^b instead of 45 to the contact 17^a.

45 The connections and apparatus just described provide means for supplying full generator potential to the cars on the track, and also for varying the potential to some extent by means of resistance. The means employed for reducing the voltage still further for braking purposes will now be described.

50 When it is desired to apply the brakes 55 the switch between switch points 19^a and 19^b is opened, and the switches between 22 and 22^a, 21 and 21^a, respectively, are closed. The result of the closing of the switch between 22 and 22^a is to cause a current to flow 60 through lead t and resistance R'' to the track 10. At a point of suitable potential along this resistance, for instance, R_b , the resistance coil is tapped by a lead z' connected to the contact point 21^a from which 65 current flows to contact 21, lead z to the

contact b^2 on the left hand side of the rheostat S. Additional contacts b' and b are provided connected to resistances R_z and R_y . When the arm of the rheostat is in contact with contact b^2 , direct connection is made with the segmental contact bx which is connected to lead 16^a, switch contacts 17^a and 17, lead 16 and conductor 15. In this way the voltage supplied to the conductor is that of the generator less the voltage drop in the resistance R_a between the points 75 22^a and R_b . The resistance R enables this reduced voltage to be regulated within small limits. An indicator is provided adapted to show whether current is flowing 80 through the resistance R'' . For this purpose current is taken from a point such as R_o of the resistance R_a by means of lead t' connected to switch contact 23^a and passed through switch contact 23, lead t' , three indicator lamps arranged in parallel between the points 24, 24^a, 25, 25^a, 26 and 26^a, and finally to the track and back to the generator.

85 The connections shown in Fig. 8 are adapted to control one section only of the conductor. For controlling a plurality of sections independently of each other the arrangement shown diagrammatically in Fig. 1 is provided.

90 In the arrangement shown in Fig. 1, A and B represent loading and discharging stations, respectively, which may be, for example, an electrically operated shovel and a dumping apparatus at a brick machine. In between the stations A and B a plurality of tracks 10, 11 are provided for shifting the loaded and empty cars from and to such stations. Each track incorporated in the system has along substantially its entire 100 length, save when interrupted for crossings and other purposes hereafter to be more specifically referred to, but a single feed conductor or "third rail" divided into a number of insulated sections 15, 15^a, 15^b, 110 and 15^c (each being controlled by a switch) through which the current for braking the cars, as well as the current for driving them, is supplied to the motors after the brakes thereof, in alternation. The switchboard C 115 is provided with four rheostats adapted to act in the manner described in connection with Fig. 8. The uppermost of these controls the potential supplied to the sections of conductor 15^c adjacent station B. The 120 next controls the sections of conductor 15^b intermediate between stations A and B. The rheostat S^2 is connected so that it can be used in place of the rheostat S for controlling the potential supplied to any of the sections of the conductor. The lowest rheostat controls the potential at the station a. It will be observed that the four rheostats are connected in parallel with the resistances R , R' . Similarly all four rheostats are con- 125 130

ected to the point R_b on the resistance R'' employed for reducing the potential to apply the brakes. There are further complications which can most readily be described by tracing the circuit from the generator to the conductor, first over the power circuits and then over the brake circuits. Beginning with the power circuit, the generator M is connected to the switch terminal 19^a, which is connected by a switch to the point 19, and thence by the leads w^3 , w^2 to the rheostat contact a^2 and resistance R' . The contacts a and a' are connected to resistance R' by leads w and w' , respectively. At a^2 connection is made with the contact c of the circuit breaker X , to be hereinafter described, which is used for protecting the relatively high potential circuit of the motor. The current then passes from a^2 to the segmental contact ax , along the lead 16^c to the contact x of the circuit breaker X , and thence to contact x' , leads 16^b, 16^a and switch terminal 17^a on the switchboard S'' ; to the switch contacts 17^b of this switchboard are connected the leads connected to the various sections of the conductor adjacent the track. As shown, three sections of the track are connected in parallel to the lead 16^a. Similarly, two of such leads are connected to each of the upper two rheostats on the board C . The rheostat S^2 is connected to all of the switch contacts 17^b opposite the contacts 17^a connected to the various track sections so that by throwing one or other of the switches upward from the point 17 any of the sections of the track can be controlled by means of the rheostat S^2 . From the contacts 17^b the current passes along lead z'' to switch contacts 17^c on the switchboard S' , and from thence to switch contacts 17^d, lead 16^x to the rheostat S^2 .

When it is desired to apply the brakes, the switch between the point 19^a and the point 19 is first opened and then the switches between points 22 and 22^a and 21 and 21^a, respectively, are closed. The point 22^a is connected to the end of the resistance R'' , and the point 21^a connected to the point R_b as described in the Fig. 8. The connections, however, between the rheostats on the board C and the switch point 21 are somewhat more complicated. In the arrangement shown in Fig. 1 the current passes from the switch contact 21 to lead z^6 , switch points 20^a, 20, lead z^5 to leads z^4 , z^3 and z^2 to the contacts b^2 on the left hand side of the rheostats on the board C . Connections are made between the resistance R and the switch contacts b , b' by the leads z and z' , respectively. From the contacts b^2 the current passes to the segmental contacts bax , and from thence to the switchboard S'' and the various sections of the conductor in the same manner as the power circuit.

The rheostat S^2 is adapted to control the braking potential in exactly the same way as the power potential.

Referring now more particularly to Fig. 2 wherein I have illustrated the car wiring it will be seen that the car is provided with a conductor 110 connected to a collector shoe (not shown) taking current from the third rail sections such as are indicated at 15 (Fig. 1) and by a conductor 111 having branches 112 and 113 to solenoidal coils 114 and 115 respectively, for operating the brake devices presently to be described, the conductor 110 being also connected by a conductor 116 to a contact point 117 on a circuit changer 118. In the circuit changer 118 as here shown I employ a solenoidal coil 119 connected by the conductor 120 to the conductor 116 and thence to the rail shoe, and connected by the conductor 121 to a resistance 122 which in turn is connected by a conductor 123 to the ground 124 through the car wheels in the customary manner; and a core 125 is actuated by the coil 119 and provided with a contact plate 126 for establishing circuit, when excited, between the contact points 117 and 117^a, but when at rest establishing circuit between the contact points 127 and 127^a. The contact point 117^a is connected by a conductor 128 to a contact 129 on a pole changing switch device 130 having blades 131, 131^a and thence by the conductor 132 connected to the contact 129^a and having branches 133, 134, to the armatures 135, 136 of the car motors which are arranged in parallel and are in turn connected by the conductors 137 and 138 to the contact point 139^a on the pole changer 130 through the return conductor 140. The contacts 127 and 127^a are respectively connected by the conductors 141 and 142 to the conductors 121 and 128 heretofore referred to, and the contact 127^a is likewise connected to the branch 116 of the main feed conductor 110 by means of a conductor 143, a resistance 144 being placed in the circuit to protect the same. The solenoidal coils 114 and 115 are arranged in parallel and connected by conductors 145 and 146 to a conductor 147 and thence by the conductors 128 and 142 to the contact point 127^a. The contact points 129^a and 139^a are connected by crossed conductors 148 and 149 to contact points 129^b and 139^b for changing the polarity of the motor armature circuits, and the contact 139 is connected by a conductor 150 and branches thereof 151 and 152 to the field windings 153 and 154 of the motors 135 and 136, such windings having connection by the conductors 155 and 156 to the ground 124 in the manner heretofore described.

As will be manifest upon consideration of the circuits above described, to the end that prompt application of the brake may not be interfered with, the solenoidal coil 119 is

should be so wound as to be unresponsive to current of less than 160 volts, but should quickly respond to current of 220 volts or over to the end that hunting of the armature 5 125 and consequently failure of the motor circuit and loss of control of the car may not ensue upon opening of the braking circuit.

Referring now more particularly to Figs. 3, 4 and 5, it will be observed that in the 10 preferred form of controller board employed by me each controller device S (see Fig. 1) is provided with an insulated base I provided with a plurality of motor contact members a a' a'' connected to the resistance 15 R' , and with a contact member ax connected to a contact x on one of the magnetic blow-out devices X, and is also provided with a plurality of brake contact members b b' b'' connected to the resistance R, and with a 20 contact member bx connected to a contact x' on one of the said devices X, all as above described.

The controller S also has a pair of contacts c and d connected respectively to the 25 contacts a'' and a point cx of the winding of the device X. The operating lever S is pivoted as indicated at p to the base I and carries a contact member m suitably secured thereto and insulated therefrom as shown at 30 i , i' , i'' , the contact m being held in operative position relatively to the several other contacts by means of a spring s . For protecting the relatively high potential motor circuit I apply to each controller device S 35 the circuit breaker mounted on a frame f secured to the base I as indicated at f' , such circuit breaker including, as here shown, the movable brush d contacting in neutral position with the contact c fixed to the base I. 40 For blowing out the arc on returning the lever S from any of the contacts a , a' , a'' to its normal position, the lever S is provided with an extension e slotted for the reception of a link l , said link having a pin p' against 45 which the extension e abuts when moved to the right but being curved at l' permitting free movement of the lever S to the left in operating the brake. The link l pivotally engages at p^2 a bell crank arm c^2 which is 50 pivotally engaged at p^4 to the frame f and in turn pivotally engages at p^5 a rod r passing through an aperture in a link l^2 which at one end is pivoted at p^6 to the frame f and at 55 the other end carries the brush d . For restoring the contact between c , d , as shown in Fig. 3, a spring s^2 is interposed between the link l^2 and the pivot point p^6 . For insuring rapid movement of the brush d upon return movement of the controller S, 60 a dash pot d^2 preferably filled with oil pivotally engages at p^6 the bell crank c^2 and within the dash pot d^2 is reciprocally mounted a plunger P pivotally engaging the link l^2 at p^7 , the head h of the plunger P having an 65 opening o controlled by a ball valve v , which

construction permits quick upward movement of the dash pot d^2 but retards its return movement. From the foregoing it will be apparent that when the lever S is thrown toward the contact a^2 the movement of the dash pot device will be as follows: The projection e through the medium of the pin p' forces the link l and the lower arm of the bell crank lever c^2 toward the left causing the dash pot d^2 to rise, the fluid passing freely from the lower portion thereof through the valve v , the head h remaining stationary, the spring s^2 on the rod r being compressed and the circuit maintained between the contact members c , d . As the handle S is returned toward the position shown the following action takes place: The liquid now in the upper portion of the dash pot is prevented from rapidly returning to the lower portion of the dash pot, and therefore in the return of the dash pot to its normal position through the action of gravity the plunger accompanies it drawing the brush d down against the pressure of the spring s^2 , which as the fluid leaks past the head h gradually restores the brush d and the other parts to the position shown. 85

The spring s^2 produces the necessary return movement of the arm l^2 as the result of the fact that at one end it bears on the arm l^2 intermediate between the pivot point p^5 of the arm and the pivot point p^7 of piston rod P of the dash pot, while at its other end it bears on the outer end of one arm of the bell crank c^2 , while the dash pot d^2 is pivotally connected at p^6 to the same arm intermediate between the pivot p^3 of the bell crank and the point of application of the force of the spring, namely, p^4 . The result is that the spring can extend more 100 readily by depressing the dash pot than by raising the arm l^2 .

Referring now more particularly to Figs. 6 and 7 wherein I have illustrated in preferred form the electrically operated brake device employed by me, it will be apparent that in the embodiment of my invention here shown the driving motor 210 of the car is supported by the axle 211 provided with wheels 212, 212' through which certain of the circuits described are grounded, and that the brake device including the solenoidal coil 114 (Fig. 2) is supported by a frame 213 extending from the motor casing. To the frame 213 is attached, as by screws 214, a split housing 215 in which the solenoidal device 114 may be held by the clamping bolt 216, the casing 210 through said frame 213 and the arm 217 also serving to support the brake jaws 218 and 219 pivoted upon the pin 220 and removably held thereupon by means of the cotter 221. Upon the jaws 218, 219 are pivotally mounted as indicated at 222 and 223 respectively brake shoes 224 and 225 adapted to bear on the 115 120 125 130 135 140 145 150 155 160 165 170 175 180 185 190 195 brake wheel 226 mounted on the shaft 227 of the armature 135, (Fig. 2) when the brake device is actuated. The brake jaws 218, 219 are held out of contact with the wheel 226 by a spring 229 and the action of gravity, respectively, save when said jaws are clamped upon the said wheel by excitation of the solenoidal coil 114 as shown in Fig. 7.

10 The springs 229 and 230 are mounted on the armature cores 231 and 232 and retained in position by being respectively interposed between said jaws 218, 219 and the casing 233 of the solenoidal coil 214 and a shoulder 15 234 on the solenoid core 232, the spring 230 being of a sufficient strength to support the core 232. It will be noted that the brake device as a whole is applied through a relatively heavy spring 235 interposed between 20 the jaw 219 and the pin 236 in the end of the core 232, thus providing for a slightly yielding braking action.

Assuming the circuit changer device 118 on the car to be actuated by a current having 25 a regular operating potential of, say 220 volts, upon throwing out of the motor circuit and throwing in of the brake circuit the constantly maintained lower potential, say, 110 volts, will be not sufficient to sustain the 30 motor circuit, which would prevent the application of the brakes, whereas when the resistance R'' is employed, upon throwing out the 220 volt motor circuit and throwing in the resistance portion R_a , such portion 35 114—115 will be in series with the brake coils 114—115 through a circuit including the members w^1 , 19, t^1 , 33, 33 ^{a} , t^1 , 22, 22 ^{a} , t , R_a , z^1 , 21 ^{a} , 21, z^2 , 20 ^{a} , 20, z^3 , z^4 , z^5 , z^6 , b^2 , b^3 , 16 ^{a} , 16 ^{b} , 17 ^{a} , 17, 16, 15, 110, 111, 112—113, 40 114—115, 147, 128, 142, 127 ^{a} , 144, 120, 119, 121, 122, 123, to ground 124, and these resistances (R_a —114—115) will be in parallel with the resistance portions R_c , R_d , grounded at w^{10} and with the motor and field windings 45 135—153, and 136—154, respectively. Under the conditions just recited the major portion of the current will at first tend to pass through the motor rather than the brake windings since the latter are pure resistances, 50 thereby causing a great drop in the voltage of the current passing through the coil 119 and allowing the core 125 to gain the position shown and establish the brake circuit, at which time the current will be divided a 55 part of the current being available to the brake windings and the remainder grounded through the wire w^{10} and the circuit described in connection therewith.

It is true that current flows through the 60 field and armature windings of the motors on the car at all times. However, when the brake coils are in operation, not only is the current reduced as the result of the lowering of the potential between the conductors 65 15 and the ground from 220 to 110 volts, but

also the potential on the field and armature coils of the motors is further reduced by reason of the fact that the motor coils are in series with the coils 144, 119, 114 and 115 (the four latter coils are also in parallel 70 with each other.) Consequently the current through the motors is relatively very small when the brakes are applied. When, however, the potential is raised to 220 volts, the voltage impressed across the terminals of 75 the motor is the full line potential owing to the fact that the coils 144, 114 and 115 are short-circuited by reason of the contact 126 bridging the contacts 117 and 117 ^{a} . At the same time solenoidal coil 119 is disconnected 80 from its previous parallel relation with respect to the coils 144, 114, 115 and comes into series with the resistance 122 alone. When the current through the motors is reduced as above indicated by lowering the 85 line potential and throwing the coils 144, 119, 114 and 115 into series with the motors, the current is not sufficient to operate the latter. The result is that the brakes and the 90 motors are not operated at the same time, but are operated in alternation as described in the specification and as specified in the claims.

When a car on the track 10 runs down grade and conductor 15 is not energized, in 95 which case the car becomes a motive power driving the motor 135, such motor in turn becomes a generator, generating current which is dissipated in the form of heat through the resistance coil 122, thus forming a retarding element or dynamic brake 100 governing the speed of the car down such grade and preventing it from running away. It is to be noted, however, that with the car operating under the conditions just described, the motor 135 does not generate current of a potential high enough to excite the 105 coil 119 sufficiently to lift the plunger 125, and consequently the circuit remains closed through the points 127, 126 and 127 ^{a} , which 110 leaves the following circuit established, starting at motor 135:—135, 133, 132, 129 ^{a} , 131, 129, 128, 142, 127 ^{a} , 126, 127, 141, 121, 122, 123, 155, 153, 151, 150, 139, 131 ^{a} , 139 ^{a} , 140, 137 back to 135. 115

Considering that the following circuit— 110, 116, 120, 119, 121, 122, 123, 124 is closed and coil 119 excited lifting plunger 125, a motor circuit is established as follows:—110, 116, 117, 126, 117 ^{a} , 128, 129, 131, 129 ^{a} , 132, 126, 133, 135, 137, 140, 139 ^{a} , 131 ^{a} , 139, 150, 151, 153, 155, 124 which has less resistance than the circuit:—110, 111, 112, 114, 145, 147, 128, 129, as above to 124 and consequently the current in the brake coil 114 will drop to 125 such a low potential as not to excite appreciably the brake coil 114 and consequently setting of the brakes is avoided.

From the above description it will be evident that in operation a car being near the 130

station A for loading will upon throwing on the controller S to excite its motor, be driven toward the terminal A until the switch 130 strikes suitable means (not shown) for reversing the current through the armature. Thereupon the loaded car will move toward the right, passing into the switch 13 and along the track 10 to the terminal B, receiving current from the feed-rail 15 and moving at a speed under control of the operator by means of the switchboards C and D, as heretofore described. Arriving at the terminal B of the track, the car will be stopped in the proper place and gradually, by the operator manipulating switchboard C, moving the controller S over to the left to throw the current from the circuit operating the motor and onto the other circuit to apply the brake. It will be observed that each section of the track can be controlled by one of the controllers S independently of any other section of the track which may be independently controlled by another controller, so that within certain limits one car can be operated without affecting the others. This individual control is obtained by means of the switch board S'. The contact 17 is connected to the sectional conductor 15, and the contacts shown to the right of it in Fig. 1 are each connected to a different sectional conductor including 15^a, 15^b and 15^c. If the contact 17 is connected by the switch with contact 17^b, the controller S' controls the car on section 15. If the switch connects contact 17 with contact 17^a, section 15 is controlled by controller S, and so on.

It will thus be seen that a single operator stationed at the electric switchboards can manipulate any one of the cars to start or stop it at any desired point on the track, and that such car when it reaches either of the terminals of the track automatically reverses its driving mechanism. This control is rendered perfect and easy by reason of the means for varying the current on any one of the several sections of track or upon all of them, so that the individual cars can be driven at any desired speed or stopped as quickly as necessary, at any part of the track where such operation may be desired. By the arrangement of the resistances to control both the driving current and the braking current I make it impossible to rack or injure the mechanism, and when desired it will be evident that the track may be in as many sections as desired and the feed-rail may everywhere parallel such track. Thus the operator has complete control over the relative positions of all the cars, and the speed of them collectively and individually at all parts of the track.

It is thought that systems illustrated employing my present invention will be fully

understood by those skilled in the art to which it pertains without greater amplification of the description of its operation.

Having thus described my invention and illustrated its use, what I claim as new and desire to secure by Letters Patent is:

1. The combination with a railway track, of a feed conductor independent of the track, means for supplying currents of different potentials to said conductor, a central switchboard having a variable resistance and a single controller to vary the currents in said conductor; and a series of independent cars on the track provided with motors and brakes, and motor and brake circuits having operative contact with said conductor.

2. The combination with a railway track, of a feed conductor independent of the track, means for supplying currents of different potentials to said conductor, a single controller to vary the currents in said conductor; and a series of independent cars on the track provided with motors and brakes, and motor and brake circuits having operative contact with said conductor.

3. The combination with a motor driven car having an electric brake, of a single feed conductor external of the car for supplying the motor and brake, and an electric controller for controlling the motor and brake in alternation from a distant point through said feed conductor.

4. The combination with a motor driven car having an electric brake, of a single feed conductor external of the car for supplying the motor and brake, and means to control the motor and brake in alternation from a distant point through said feed conductor.

5. The combination with a plurality of motor driven cars each having an electric brake, of a single feed conductor for the motor and brake, and means for controlling the motors and the brakes of the cars in alternation from a distant point.

6. The combination with a plurality of motor driven cars each having an electric brake, of a single feed conductor for the motor and brake, and means for controlling as well the several motors as the several brakes in sequence from a distant point.

7. The combination with a plurality of motor driven cars each having an electric brake, of a single feed conductor external of the car for supplying the motor and brake, and means for controlling them at will from a distant point through said feed conductor.

8. The combination with a plurality of motor driven cars each having an electric brake, of a single feed conductor external of the car for supplying the motor and brake, and means for controlling said motor and brake at will from a distant point through

said feed conductor and operating them independently of each other.

9. The combination with a plurality of motor driven cars each having an electric 5 brake, of a single feed conductor external of the cars for supplying the motors and brakes, and means for controlling the motors and the brake devices of the cars in alternation from a distant point through said 10 feed conductor.

10. The combination with a plurality of motor driven cars each having an electric 15 brake, of a single feed conductor external of the cars for supplying the motors and brakes, and means for controlling the motors and the brake devices of the cars in alternation from a distant point through said 20 feed conductor independently of any other car.

20 11. The combination with a motor driven car provided with a brake, of means for supplying current to said motor and brake comprising a supply conductor, means for varying the potential of the current supplied 25 to said conductor, and means on the car for directing current of relatively higher potential to the motor and current of relatively lower potential to the brake.

20 12. The combination with a motor driven car provided with a brake, of means for supplying current to said motor and brake comprising a supply conductor, means for varying the potential of the current supplied 35 to said conductor, and means on the car for directing current of one potential to the motor and current of another potential to the brake.

30 13. The combination with a motor driven car provided with a brake, of means for 40 supplying current to said motor and brake comprising a supply conductor, means for varying the potential of the current supplied to said conductor, and means on the car for directing current greater than a certain potential to the motor and less than a certain potential to the brake.

45 14. The combination with a motor driven car provided with a brake, of means for supplying current to said motor and brake comprising a supply conductor, means for varying the potential of the current supplied to said conductor and a circuit changer on the car provided with means responsive to current of a relatively high potential for directing the same to the motor, said means being non-responsive to current of a relatively low potential and arranged for diverting the same to the brake.

55 15. The combination with a motor driven car provided with a brake, of means for supplying current to said motor and brake comprising a supply conductor, means for varying the potential of the current supplied to said conductor and a circuit changer on the car provided with means responsive

to current of one potential, and non-responsive to current of another potential and arranged to direct current of one potential to the motor and divert current of another potential to the brake.

70 16. The combination with a motor driven car provided with a brake, of means for supplying current to said motor and brake comprising a supply conductor, means for varying the potential of the current supplied to said conductor and a circuit changer on the car provided with means responsive to current higher than a certain potential and non-responsive to a current lower than a certain potential, and arranged to direct 75 current of one potential to the motor and divert current of another potential to the brake.

75 17. The combination with a motor driven car provided with a brake, of means for supplying current to said motor and brake comprising a supply conductor, means for varying the potential of the current supplied to said conductor and a circuit changer on the car provided with means responsive to current of one potential and non-responsive to current of another potential and arranged to direct current of one potential to the motor and divert current of another potential to the 80 brake.

80 18. The combination with a circuit of track, a series of cars thereon, provided with electric motors and brakes, and a sectional conductor for supplying current to the same, of a central switchboard having means to vary the potential and the flow of the current in certain sections of the conductor independently of the potential of the current in other sections.

85 19. The combination with a circuit of track, a series of cars thereon, each provided with electric motors and brakes, and a sectional conductor for supplying current to the same, of a central switchboard having means to vary the potential of the conductor and the strength of the current flowing therethrough in certain sections independently of the other sections.

90 20. The combination with a circuit of track, a series of cars thereon, provided with electric motors and brakes, and a sectional conductor for supplying current to the same, of a central switchboard having means to differentially vary the current and the potential of the current in different sections of the conductor independently of the other sections.

100 21. The combination with a circuit of track, a series of cars thereon, provided with electric motors and brakes, and a conductor for supplying current to the same, of a central switchboard having means to differentially vary the current and the potential 105

- of the current in said conductor and electrical connections between said conductor and said motors, brakes, and switchboard respectively.

5. The combination with a car having an electric motor and an electric brake, a track and a conductor for feeding the motor and brake, of a single central controller for varying the potential of the current for controlling both the motor and the brake from a distant central station.

10. The combination with a car having an electric motor and an electric brake, a track and a conductor for feeding the motor and brake, of a single central controller for differentially varying the potential of the current for controlling both the motor and the brake from a distant central station.

15. The combination with a motor driven car, having thereon an electrical brake, of a distant controller controlling station and a single feed conductor therefrom to the motor and brake, and a single controller having connections to means for supplying currents of different potentials and adapted to alternately energize the motor and the brake.

20. The combination with a motor driven car having thereon an electrical brake, of a distant controlling station and a single feed conductor therefrom to the motor and brake, and a single controller having connections to means for supplying currents of different potentials and adapted to alternately energize the motor and the brake, and means attached thereto to vary the strength of current in each conductor.

25. The combination with a motor driven car having an electric brake, of a single feed conductor for supplying current to the motor and brake, and an electric controller for controlling said motor and brake in alternation through a variation in the potential of the current supplied through said feed conductor.

30. The combination with a motor driven car having an electric brake, of a single feed conductor for supplying current to the motor and brake, and means for controlling said motor and brake in alternation through a variation in the potential of the current supplied through said feed conductor.

35. The combination with a motor driven car having an electric brake, of a single feed conductor for supplying current to the motor and brake, and an electric controller for controlling said motor and brake in alternation through a variation in the potential of the current supplied through said feed conductor.

40. The combination with a motor driven car having an electric brake, of a single feed conductor for supplying current to the motor and brake, and an electric controller for controlling said motor and brake in alternation through a variation in the potential of the current supplied through said feed conductor.

45. The combination with a motor driven car having an electric brake, of a single feed conductor for supplying current to the motor and brake, and means for controlling said motor and brake in alternation through a variation in the potential of the current supplied through said feed conductor.

50. The combination with a motor driven car having an electric brake, of a single feed conductor for supplying current to the motor and brake, and an electric controller for controlling said motor and brake in alternation through a variation in the potential of the current supplied through said feed conductor.

55. The combination with a motor driven car having an electric brake, of a single feed conductor for supplying current to the motor and brake, and an electric controller for controlling said motor and brake in alternation through a variation in the potential of the current supplied through said feed conductor and for controlling the speed of said motor and the strength of the application of said brake through a variation in the strength of such current.

60. The combination with a motor driven car having an electric brake, of a single feed conductor for supplying current to the motor and brake, and means for controlling said motor and brake in alternation through a variation in the potential of the current supplied through said feed conductor.

65. The combination with a motor driven car having an electric brake, of a single feed conductor for supplying current to the motor and brake, and an electric controller for controlling said motor and brake in alternation through a variation in the potential of the current supplied through said feed conductor.

70. The combination with a motor driven car having an electric brake, and means for controlling said motor and brake in alternation through a variation in the potential of the current supply through said feed conductor and for controlling the speed of said motor and the strength of the application of said brake through a variation in the strength of such current.

75. The combination with a motor driven car having an electric brake, and a single feed conductor for supplying current to the motor and the brake, a source of current adapted to give relatively high and relatively low potential, one for operating said motor and another for operating said brake, and means for controlling the supply of current from said sources to said conductor.

80. The combination with a motor driven car having an electric brake and a single feed conductor for supplying current to the motor and the brake, a source of current adapted to give relatively high and relatively low potential, one for operating said motor and another for operating said brake, and means for controlling the supply of current from said sources to said conductor, the car being supplied with means for directing current of one potential to the motor and current of another potential to the brake.

85. The combination with a motor driven car having an electric brake and a single feed conductor for supplying current to the motor and the brake, a source of current adapted to give relatively high and relatively low potential, one for operating said motor and another for operating said brake, and means for controlling the supply of current from said sources to said conductor, the car being supplied with means for directing current of one potential to the motor and current of another potential to the brake.

90. The combination with a motor driven car having an electric brake and a single feed conductor for supplying current to the motor and the brake, a source of current adapted to give relatively high and relatively low potential, one for operating said motor and another for operating said brake, and means for controlling the supply of current from said sources to said conductor, the car being supplied with means for directing current of one potential to the motor and current of another potential to the brake.

95. The combination with a motor driven car having an electric brake and a single feed conductor for supplying current to the motor and the brake, a source of current adapted to give relatively high and relatively low potential, one for operating said motor and another for operating said brake, and means for controlling the supply of current from said sources to said conductor, the car being supplied with means for directing current of one potential to the motor and current of another potential to the brake.

100. The combination with a car having a motor and a brake, both electrically actuated, and a single feed conductor for supplying current thereto, of a main source of current of relatively high potential for energizing one of said electrically actuated devices, means for dividing the current from said source of supply whereby part of the divided current may be supplied for energizing the other of said electrically actuated devices and controlling means for supplying either undivided current from said main source, or a divided part thereof, to said feed conductor.

105. The combination with a car having a motor and a brake, both electrically actuated, and a single feed conductor for supplying current thereto, of a main source of current of relatively high potential for energizing one of said electrically actuated devices, means for dividing the current from said source of supply whereby part of the divided current may be supplied for energizing the other of said electrically actuated devices and controlling means for supplying either undivided current from said main source, or a divided part thereof, to said feed conductor.

110. The combination with a car having a motor and a brake, both electrically actuated, and a single feed conductor for supplying current thereto, of a main source of current of relatively high potential for energizing one of said electrically actuated devices, means for dividing the current from said source of supply whereby part of the divided current may be supplied for energizing the other of said electrically actuated devices, variable resistance means and controlling means for supplying either undivided current from said main source, or a divided part thereof, to said feed conductor, either directly or through said variable resistance means.

115. The combination with a car, means for driving the car adapted in turn to be driven by the car, a brake for the car, independent automatic means for retarding said driving means when said driving means is

120. The combination with a car, means for driving the car adapted in turn to be driven by the car, a brake for the car, independent automatic means for retarding said driving means when said driving means is

125. The combination with a car, means for driving the car adapted in turn to be driven by the car, a brake for the car, independent automatic means for retarding said driving means when said driving means is

driven by the car, means for operating the motor, and alternately acting means for operating the brake, the said retarding means being arranged to operate when the means for operating the motor is at rest.

35. The combination of a car, means for driving the car adapted in turn to be driven by the car, a brake for the car, independent means for retarding said driving means when said driving means is driven by the car, means for operating the motor, and alternately acting means for operating the brake, the said retarding means being arranged to operate when the means for operating the motor is at rest.

36. The combination of a car, a motor for driving the car, a brake for the car, independent means for retarding said motor when said motor is driven by the car, means for operating the motor, and alternately acting means for operating the brake, the said retarding means being arranged to operate only when the means for operating the motor is at rest.

37. The combination of a car, a motor for driving the car, a brake for the car, independent automatic means for retarding said motor when said motor is driven by the car, means for operating the motor, and alternately acting means for operating the brake, the said retarding means being arranged to operate only when the means for operating the motor is at rest.

38. The combination of a car, means for driving the car adapted in turn to be driven by the car, independent automatic means for retarding the car when said car drives said motor, means for operating the motor, and alternately acting means for operating the brake, the said retarding means being arranged to operate when the means for operating the motor is at rest.

39. The combination of a car, means for driving the car adapted in turn to be driven by the car, a brake for the car, independent means adapted to retard said driving means when the car descends a grade, means for operating the motor, and alternately acting means for operating the brake, the said retarding means being arranged to operate when the means for operating the motor is at rest.

40. The combination of a car, an electric motor, a driving connection between the motor and the car, electrically operated means for braking the car, suitable means for supplying current to said motor and braking means, and means for automatically inserting resistance in the motor circuit when said motor is propelled by the car, the said several elements being so arranged that the motor responds when current of one potential is supplied to said current supply means, the braking element responds when current of another potential is supplied to said current

supply means, and the resistance opposes the motor when the current supply is discontinued.

41. The combination of a car, an electric motor, a driving connection between the motor and the car, electrically operated means for braking the car, suitable means for supplying current to said motor and braking means, and means for inserting resistance in the motor circuit when said motor is propelled by the car, the said several elements being so arranged that the motor responds when current of one potential is supplied to said current supply means, the braking element responds when current of another potential is supplied to said current supply means, and the resistance opposes the motor when the current supply is discontinued.

42. The combination of a car, an electric motor for driving the car, electrically operated means for braking the car, suitable means for supplying current to said motor and braking means, and means for automatically retarding the motor and thereby the car when said motor is driven by the car, the said several elements being so arranged that the motor responds when current of one potential is supplied to said current supply means, the braking element responds when current of another potential is supplied to said current supply means, and the retarding means opposes the motor when the current supply is discontinued.

43. The combination of a car, an electric motor for driving the car, electrically operated means for braking the car, suitable means for supplying current to said motor and braking means, and means for retarding the motor and thereby the car when said motor is driven by the car, the said several elements being so arranged that the motor responds when current of one potential is supplied to said current supply means, the braking element responds when current of another potential is supplied to said current supply means, and the retarding means opposes the motor when the current supply is discontinued.

44. The combination of a car, an electric motor for driving the car, electrically operated means for braking the car, suitable means for supplying current to said motor and braking means, and dynamic brake means for retarding the motor and thereby the car when said motor is driven by the car, the said several elements being so arranged that the motor responds when current of one potential is supplied to said current supply means, the electric braking means responds when current of another potential is supplied to said current supply means, and the dynamic brake means opposes the motor when the current supply is discontinued.

45. The combination of a car, an electric motor for driving the car, electrically operated means for braking the car, suitable means for supplying current to said motor and braking means, dynamic brake means for retarding the car when said car drives said motor, and a circuit changer, the said several elements being so arranged that the motor responds when current of one potential is supplied to said current supply means, the electric braking means responds when current of another potential is supplied to said current supply means, and the dynamic brake means opposes the motor when the current supply is discontinued.
46. The combination of a car, an electric motor for driving the car and adapted in turn to be driven by the car, electrically operated means for braking the car, suitable means for supplying current to said motor and said braking means, and a dynamic brake element, the said dynamic brake element being relatively short-circuited with respect to the motor supply means when motor current is being supplied to the motor and is placed in circuit with the motor when the motor current supply to the motor is discontinued.
47. The combination of a car, an electric motor for driving the car and adapted in turn to be driven by the car, electrically operated means for braking the car, suitable means for supplying current to said motor and said braking means, a dynamic brake element, and a circuit changer whereby the said dynamic brake element is relatively short-circuited with respect to the motor supply means when motor current is being supplied to the motor and is placed in circuit with the motor when the motor current supplied to the motor is discontinued.
48. The combination of a car, an electric
- motor for driving the car, electrically operated means for braking the car, dynamic means for retarding the car, and suitable connections between said several elements so arranged that said driving means responds to a current of one potential, said braking means responds to current of another potential, and said retarding means operates when said motor is driven by said car.
49. The combination of a car, an electric motor for driving the car, electrically operated means for braking the car, automatically-operable dynamic means for retarding the car, and suitable connections between said several elements so arranged that said driving means responds to a current of one potential, said braking means responds to current of another potential, and said retarding means operates when said motor is driven by said car.
50. The combination of a car, an electric motor for driving the car, electrically operated means for braking the car, a feed conductor, a circuit changer, circuits between said conductor and said motor and braking means including the circuit changer, and a dynamic brake element, the said several elements being so arranged that the motor responds when current of one potential is supplied to said feed conductor, the braking means responds when current of another potential is supplied to said feed conductor and the dynamic brake element is placed in series with and opposes the motor when the current is discontinued.

In testimony whereof I have hereunto signed my name in the presence of the two subscribed witnesses.

FRANK E. WOODFORD.
